EDGE SUPPORT FOR THE OPENING OF
VACUUM CLEANER BAGS OR THE LIKE

Frank S. Howard, Chicago, Ill., assignor to Birtman Electric Company, a corporation of Illinois

Application November 12, 1946, Serial No. 709,283

4 Claims. (Cl. 150—1)

1

This invention relates to a bag construction and particularly to a bag for a vacuum cleaner wherein the dirt is separated from the air.

Practically all of the floor model vacuum cleaners employ a bag into which dirt-laden air is directed. The bag serves as a filter to separate the dirt from the air with the air going through the walls of the bag and the dirt remaining within the bag. It is necessary, therefore, that the bag be emptied from time to time in order that it function with the greatest efficiency. An opening is ordinarily provided in the bag for emptying the dirt, with this opening being normally kept closed with a clamp that holds the sides of the opening pressed tightly against each other. This opening is usually at the top of the bag and the top portion is suspended from the handle of the cleaner by a short chain, or the like, attached to the clamp.

In order that the opening be kept tightly closed, it is necessary that the sides of the opening be folded flat against each other in a particular manner. Ordinarily the bag has an opening provided with two oppositely disposed folds directed inwardly and with two non-folded portions against which the clamp bears. The two folded portions are ordinarily held between the non-folded portions. It has been found in practice that it is difficult to arrange the opening of the bag so that the folded portions will be held between the non-folded portions when the clamp is in place. If the folded sides of the bag at the fold lines sag, there is always the possibility that the bag will leak air and dirt at the opening thereby reducing the efficiency of the bag and permitting dirt to escape into the room. In order to overcome this disadvantage, the present invention is directed to a reinforcement for the bag opening so that the opening may be easily folded into its proper position before applying the clamp.

In order to accomplish this, the bag is provided with a rigid reinforcement having a portion extending along one edge of a folded section to the fold line. Another portion of the reinforcement is fastened to a part of the edge of the opening. This reinforcement serves to hold the fold up near the plane of the opening even when the clamp is removed and the opening is fully extended. The invention broadly comprises a flexible container having an opening, a reinforcement for at least a part of the edge of the opening comprising a rigid member having one portion fastened to and lying along said edge part and a second portion fastened to a part of the container spaced from the edge of the opening. The invention is

2

applicable not only to a vacuum cleaner bag, but to any container having flexible walls and an opening therein.

The invention will be described as related to 5 one embodiment of the same as set out in the accompanying drawings. Of the drawing, Fig. 1 is an elevation of a vacuum cleaner having a bag attached thereto with the bag embodying the invention; Fig. 2 is a perspective view of the top 10 of the bag showing the opening in a distended position; Fig. 3. is a plan view of the distended opening; Fig. 4 is a plan view of the opening in closed position; and Fig. 5 is a fragmentary perspective view of a portion of the opening with 15 sections broken away for clarity of illustration.

The vacuum cleaner shown in the accompanying 20 drawings comprises a body portion 10 including a nozzle 11, front supporting wheels 12, intermediate wheels 13, rear wheels 14, a handle 15 including an end 16 adapted to be grasped by the hand, and a bag 17 attached to the outlet 18 of the body portion 10.

The bag 17 is provided with a top opening 19 normally kept closed by a clamp 20 having a substantially U-shaped cross section. The clamp 20 is suspended from the handle by a short chain 21, or the like, attached to the handle.

The opening 19 of the bag has two straight side 25 portions 22 of substantially equal length and two end portions 23 also of substantially equal length. The end portions 23 are adapted to be folded inwardly to close the opening as shown in Fig. 4. Each end portion has a fold line 24 at substantially the center.

Each side portion 22 of the opening is provided 30 with a flat bar 25 of slightly shorter length than its corresponding side with the bar being located in a pocket 26 formed by folding over a section of the side of the bag and sewing it to produce a seam 27.

In order to support the side portions 23 of the 35 opening when the opening is extended, there are provided a pair of rod members 28 with each rod member being bent at substantially its middle portion to form an approximately 90° angle. One leg 29 of a rod member is stitched to the edge of the opening between the fold line 24 and the corner adjacent an end of a bar 25. The other leg of the rod member is stitched to the bag 17 in a downwardly extended position, as by spaced 40 stitches 30, and is arranged at substantially 90° to the plane of the opening. The other rod member 28 is similarly arranged at the other side of the bag and adjacent the other end of the 45 same bar 25.

With the construction described above, the sides 23 of the opening are held by the rod members 28 even when the opening is fully distended so that the opening at all times is in a substantially flat plane. Because the rod members support the sides of the opening, it is very simple to fold the opening to a closed position before applying the clamp 20. There is no danger of the sides sagging and permitting leakage of air and dirt. With this construction, it is a very simple matter to close the opening as the folds at the fold lines 24 need not be pulled into position before applying the clamp.

The pockets in which the bar members 25 and the rod members 28 are held are sufficiently resilient that the clamp completely closes the opening. In order to assist in forming an airtight closure, it is preferred that the bar members 25 be made slightly shorter than their corresponding sides of the opening. This permits the downwardly extended portions of the rod members 28 to be arranged beyond the bar members when the opening is closed, as shown in Fig. 4.

Having described my invention as related to the embodiment shown in the accompanying drawings, it is my intention that the invention be not limited by any of the details of description unless otherwise specified, but rather be construed broadly within its spirit and scope as set out in the accompanying claims.

I claim:

1. A vacuum cleaner bag having an opening therein, an inwardly-directed fold in the bag adjacent the edge of the opening with the fold having two side portions, a reinforcing means comprising a bar member bent intermediate its ends to form two portions lying at an angle of approximately 90°, means for fastening one portion of the bar member to one side portion of the fold along the edge of the opening, and means for rotatably fastening the other portion of the bar member to the bag substantially at a corner portion thereof and at an angle of approximately 90° with respect to the plane of the opening.

2. A vacuum cleaner bag having an opening therein, inwardly-directed folds on two opposite sides of the opening with each fold having an inwardly-directed fold line, a reinforcing means comprising a bar member bent at an approximately 90° angle, means for fastening one portion of the bar member to one side of a fold along the edge of the opening with the end of the bar member being adjacent a fold line, with the angle of the bar member being adjacent the angle formed by said side of the fold and the straight contiguous side of the opening adjacent

said side of the fold, means for rotatably fastening the second portion of the bar member to the bag at an angle of approximately 90° with respect to the plane of the opening, a second bar member similarly bent and fastened to the second fold in a manner similar to that of the first bar member, a rigid substantially straight reinforcing means fastened to said contiguous side of the opening, and a second rigid substantially straight reinforcing means fastened to another straight side of the opening.

3. In a vacuum cleaner bag having an opening with the bag being foldable along fold lines extending inwardly from said opening, a reinforcing means for at least a part of the edge of said opening comprising a rigid member having angularly disposed leg portions, one leg portion being fastened to and lying along an edge of the opening and the entire other leg portion being rotatably fastened to said bag adjacent to a fold line.

4. A vacuum cleaner bag having an opening therein having the shape of a four-sided parallelogram when fully open, inwardly-directed folds on two opposite sides of the opening with each fold having a fold line at substantially the center thereof, a rigid substantially straight reinforcing means attached to a non-folded side of the opening, a second rigid substantially straight reinforcing means attached to the other non-folded side of the opening, each of said reinforcing means being slightly shorter in length than the corresponding side of said opening, a bar member bent at an angle of approximately 90° having one leg of the angle fastened to a folded side of the opening with the leg extending between the fold line and an edge of said folded side, a second bar member bent at an angle of approximately 90° having one leg of the angle fastened to the other folded side of the opening with the leg extending between the fold line and an edge of said other folded side, means for rotatably fastening the other leg of said first angle to the bag and means for rotatably fastening the other leg of said second angle to the bag.
